PREPARATION OF RACEMIC SANTONIN

Yasuo Abe, Ikeda, Osaka, Tadatsugu Harukawa, Sakyo-ku, Kyoto, Hisashi Ishikawa, Higashinada-ku, Kobe, Takuichi Miki, Amagasaki, Hyogo, Masao Sumi, Ikeda, Osaka, and Tadashi Toga, Ashiya, Hyogo, Japan, assignors to Takeda Pharmaceutical Industries, Ltd., Higashi-ku, Osaka, Japan

No Drawing. Application April 19, 1954
Serial No. 424,284

Claims priority, application Japan September 30, 1953

6 Claims. (Cl. 260—343.3)

This invention relates to optically active and inactive stereoisomers of santonin.

The isomers have the common structure representable by the following formula:

Since C₅, C₆, C₉ and C₁₁ in the above formula are all asymmetric carbon atom, theoretically 16 optically active isomers and corresponding 8 racemates are possible for the formula. The present invention relates to 4 racemates and 2 optically active isomers out of the above mentioned possible isomers. These compounds were synthesized for the first time by the present inventors. The steric configurations of them are shown as follows:

2

The 4 racemates in the present invention are explained as follows:

(A) The optically inactive stereoisomeride consisting of equivalent amounts of II and Id. It is designated as racemic santonin C.

(B) The optically inactive stereoisomeride consisting of equivalent amounts of III and IIId. It is designated as racemic santonin D.

(C) The optically inactive stereoisomeride consisting of equivalent amounts of IIIId and IVd. It is designated as racemic α -santonin.

(D) The optically inactive stereoisomeride consisting of equivalent amounts of IVI and IVd. It is designated as racemic β -santonin.

15 15 The 2 optically active isomers in the present invention are explained as follows:

(E) The optically active compound representable by the Formula IIId. It is designated as dextrorotatory α -santonin.

20 20 (F) The optically active compound representable by the Formula IVd. It is designated as dextrorotatory β -santonin.

In general these compounds are almost insoluble in water, sparingly soluble in ether and petroleum, but they 25 are soluble in a variety of hot organic solvents, such as methanol, ethanol, chloroform, ether, benzene, acetone and petroleum etc., and in aqueous solution of alkali.

These compounds as a whole show the absorption band 30 characteristic of α,β,β -trisubstituted α,β -unsaturated ketone in the ultra-violet region. They are effective as antihelmintic and in some of them the activity is almost equal to that of natural santonin. Many of them are less toxic than natural santonin and some of them show half the toxicity of natural santonin.

35 35 By the action of sodium methylate in methanol all these compounds display the pink color characteristic of natural santonin, but the color reaction is rather weak in the case of santonin C or D.

40 40 Next, detailed explanations are made on the individual uses of the compounds.

(a) Racemic santonin C is recrystallized from methanol into colorless prisms, M. P. 180° C. When subjected to dienone-phenol rearrangement by heating with 55% sulfuric acid at 50° C., it is converted into rac. α -desmotroposantonin, M. P. 198° C. The ultra violet spectrum of the compound has an absorption maximum at 247 m μ (log ϵ =4.15) but it shows no such a characteristic shoulder in the vicinity of 270 m μ as is seen in natural santonin.

(b) Racemic santonin D is recrystallized from methanol into colorless prisms, M. P. 190° C. This compound has an absorption maximum at 245 m μ (log ϵ =4.19). When subjected to rearrangement with 55% sulfuric acid, it is converted into racemic β -desmotroposantonin, M. P. 232° C.

(c) Racemic α -santonin is recrystallized from methanol into colorless plates, M. P. 181° C. This compound has an absorption maximum at 241 m μ (log ϵ =4.28) and shows a shoulder in the vicinity of 270 m μ in accordance with those of natural santonin. The infra-red spectra 60 60 of this compound also well accord with those of natural santonin. When subjected to dienone-phenol rearrangement by heating with 55% sulfuric acid at 50° C., it is converted into racemic α -desmotroposantonin.

(d) Racemic β -santonin is recrystallized from methanol 65 into colorless rhombic plates, M. P. 186° C. This compound has an absorption maximum at 242 m μ (log ϵ =4.19) and show a characteristic shoulder in the vicinity of 270 m μ . The infra-red spectra of this compound well accord with those of natural santonin. Both the α - and β -santonins are racemates which correspond to natural α -santonin and natural β -santonin, respectively. When 70

subjected to dienone-phenol rearrangement by heating with 55% sulfuric acid at 50° C., it is converted into racemic β -desmotroposantoin.

(e) Dextrorotatory- α -santonin or (+)- α -santonin is recrystallized from methanol into colorless rectangular plates, M. P. 172° C. The ultra-violet and infra-red spectra of this compound well accord with those of natural santonin. The specific rotatory power of this compound is $[\alpha]_D^{20}=+168^\circ$ (2% solution in alcohol) and it is the antipode of natural 1- α -santonin. This compound is converted into d- α -desmotroposantoin through the dienone-phenol rearrangement.

(f) Dextrorotatory- β -santonin or (+)- β -santonin is recrystallized from methanol into colorless prisms, M. P. 215° C. The specific rotatory power of this compound is $[\alpha]_D^{20}=+137^\circ$ (2% solution in chloroform) and it is the antipode of natural β -santonin. This compound is converted into d- β -desmotroposantoin through the dienone-phenol rearrangement.

The methods for manufacturing them are explained as follows:

(a) Rac.-santonin C.—The Michael condensation of 3-keto-4,9-dimethyl-1,2,3,7,8,9-hexahydronaphthalene with diethylmethylmalonate in the presence of sodium methylate gave rac.-diethyl (3-keto-4,9-dimethyl-1,2,3,5,6,7,8,9-octahydro-6-naphthyl)-methylmalonate, which, on alkaline hydrolysis (the free acid melts at 204° C. with decomposition) and subsequent decarboxylation, yielded a mixture of substituted propionic acids epimeric at C₁₁. An isomer of rac.- α -(3-keto-4,9-dimethyl-1,2,3,5,6,7,8,9-octahydro-6-naphthyl)-propionic acid, M. P. 135° C. (designated as D-acid) was obtained by recrystallization from ethyl acetate-petroleum ether and subsequently from methanol-water. The mother liquors of the ethyl acetate-petroleum ether recrystallization were concentrated and the separating crystalline material was recrystallized from methanol-water to afford another isomer of the acid, M. P. 145° C. (designated as C-acid). Bromination of C-acid gave the lactone of rac.- α -(3-keto-2-bromo-4,9-dimethyl-5-hydroxy-1,2,3,5,6,7,8,9-octahydro-6-naphthyl)-propionic acid, M. P. 145° C. (dec.), and this was dehydrobrominated with boiling collidine to rac.-santonin C, M. P. 180° C.

(b) Rac.-santonin D.—Rac.-santonin D was prepared from rac.-D-acid, M. P. 135° C., by the same procedure as described on the preceding experiment for rac.-santonin C via bromolactone D (M. P. 143° C. dec.). This was recrystallized from methanol to colorless prisms, M. P. 190° C.

(c) Rac.- β -santonin.—To a solution of rac.-C- and -D-acid in glacial acetic acid, selenium dioxide and a small amount of water was added and refluxed for 4 hours. The precipitating selenium was filtered off, and the filtrate was distilled at a reduced pressure. The residue was extracted with ether, and the ether extract was washed with sodium carbonate solution and water successively, and dried over anhydrous sodium sulfate. On evaporation of the ether, a crystalline material separated from the residue, which on recrystallization from methanol gave colorless prisms of rac.- β -santonin, M. P. 186° C.

(d) Rac.- α -santonin.—From the mother liquor of rac.- β -santonin, described in the preceding example, was obtained another crystalline product, viz., rac.- α -santonin. This was recrystallized from aqueous methanol as colorless rectangular plates, M. P. 181° C.

(e) d- α -Santonin or (+)- α -santonin.—On treatment with selenium dioxide or by bromination and subsequent dehydrobromination of diethyl 3-keto-4,9-dimethyl-1,2,3,5,6,7,8,9-octahydro-6-naphthyl methylmalonate, a double bond was introduced between C₁ and C₂ positions and the resulting dienone-ester was saponified with alcoholic potassium hydroxide to give rac.- α -(3-keto-4,9-dimethyl-3,5,6,7,8,9-hexahydro-6-naphthyl)-methylmalonic acid.

Resolution of this dienone-acid was effected via the brucine or quinone salt, and the laevo acid thus obtained was decarboxylated to an isomeric mixture of two optically active α -(3-keto-4,9-dimethyl-3,5,6,7,8,9-hexahydro-6-naphthyl)-propionic acids epimeric at C₁₁.

This material was boiled with selenium dioxide in acetic acid for several hours. After precipitating selenium was removed by filtration, and the solvent was evaporated to leave a crude mixture of d- α - and d- β -santonin.

When heated with methanolic potassium hydroxide, the crude santonin isomers were changed to a mixture of the corresponding potassium santoninates. The solution was acidified with hydrochloric acid, and d- α -santonin was obtained from the easily lactonizing part, as colorless rectangular plates, M. P. 172° C.

(f) d- β -Santonin or (+)- β -santonin.—The velocity of lactonization of d- β -santoninic acid is slower than that of d- α -isomer.

After d- α -santonin was removed in the manner described in Example e, the acidified solution was warmed on the water bath affording d- β -santonin as colorless rhombic prisms, M. P. 215° C.

All melting points are uncorrected.

This invention also relates to a process for preparing racemic santonin D.

That is, hydrolysis of racemic α -(3-keto-4,9-dimethyl-1,2,3,5,6,7,8,9-octahydro-6-naphthyl)-propionic acid alkyl ester (V) prepared by the method given in "Proceeding of the Japan Academy" 28, 425 (1952) and J. Am. Chem. Soc. 75, 2567 (1953), gives an isomeric mixture, from which two isomers, racemic α -(3-keto-4,9-dimethyl-1,2,3,5,6,7,8,9-octahydro-6-naphthyl)-propionic acid-A (VIa: designated as A-acid, M. P. 181° C.) and -B (VIb: designated as B-acid, M. P. 120-125° C.), were crystallized. Exhaustive separation of the A and B acids leaves behind an acidic substance containing another acid, M. P. 135° C. (VId: designated as D-acid) and halogenation of the substance by two moles of halogen or by the Wohl-Ziegler's procedure for allyl halogenation with two moles of reagent yields racemic α -(3-keto-4,9-dimethyl-2-halogeno-5-hydroxy-1,2,3,5,6,7,8,9-octahydro-6-naphthyl)-propionic acid lactone (VII).

As halogenating agent by the Wohl-Ziegler's method are cited, for example, N-succinic imidobromide, N-phthalic imidobromide, N-succinic imidochloride and N-phthalic imidochloride.

In the above mentioned halogenation of D-acid racemic α -(3-keto-4,9-dimethyl-2,5-dihalogeno-1,2,3,5,6,7,8,9-octahydro-6-naphthyl)-propionic acid is isolated as an intermediate in some experiments, but treatment of this compound with a basic reagent such as carbonates of alkali and alkaline earth metal gives rise to the halogenolactone (VII) under splitting off the halogen at C₅ with the hydrogen of the carboxyl at C₁₁ as hydrogen halide.

On the other hand, the C₂-halogeno-lactone (VII) is also obtained by mono halogenation of D-acid (VId: M. P. 135° C.) to form α -(3-keto-4,9-dimethyl-5-hydroxy-1,2,3,5,6,7,8,9-octahydro-6-naphthyl)-propionic acid lactone (VIII) followed by halogenation at C₂.

Treatment of the halogenolactone (VII) with a basic reagent, for example, collidine, pyridine, piperidine, picoline, N,N-dialkylaniline, primary or secondary amine, silver oxide, carbonates and bicarbonates of alkali and alkaline earth metal or neutral salts such as lithium chloride, magnesium chloride in dimethyl formamide, introduces a double bond between C₁ and C₂, producing the desired product, racemic santonin D. This product, M. P. 190° C., has absorption maximum at 245 m μ (log $\epsilon=4.19$), and when subjected to dienone-phenol rearrangement by heating with 55% sulfuric acid at 50° C. it is converted into racemic β -desmotroposantoin.

Analysis.—Calcd. for C₁₅H₁₈O₃: C, 73.14; H, 7.37. Found: C, 73.00; H, 7.41.

The reactions in this invention are shown in the following scheme:

All melting points are uncorrected.

Example 1

Twenty-five grams of the mother liquors of rac.-A and -B-acid (cf. Proc. Japan Acad. 28, 425 (1952); J. Am. Chem. Soc. 75, 2567 (1953)), in 250 cc. of ether were agitated, and to this was gradually added a solution of 48 g. of bromine in 250 cc. of acetic acid at room temperature. The ether was removed under reduced pressure and the residue poured into a large quantity of water, extracted with ether, and the ether solution was washed with water, sodium bicarbonate and water again. After being dried over sodium sulfate, the solution was concentrated to leave a small amount of ether. Filtration gave 0.7 g. of crystalline substance, which was recrystallized from methanol to afford the lactone of rac. α -(3-keto-4,9-dimethyl-2-bromo-5-hydroxy-1,2,3,5,6,7,8,9-octahydro-6-naphthyl)-propionic acid (VII) as colorless plates, M. P. 180° C. dec.

A mixture of 0.7 g. of the above lactone and 5 cc. of γ -collidine was heated at 140–150° C. for an hour. The reaction mixture was cooled, taken up in ether, and the ether solution was washed with water, diluted sulfuric acid, water, sodium carbonate and water by turns, dried and evaporated. The crystalline material was filtered and

recrystallized from methanol to furnish the lactone of rac. α -(3-keto-4,9-dimethyl-3,5,6,7,8,9-hexahydro-6-naphthyl)-propionic acid as prisms, M. P. 190° C., which was designated as rac.-santonin D (IX).

Example 2

To a suspended solution of 4 g. of rac.-D-acid in 140 cc. of ether containing a few drops of hydrogen bromide-
 10 acetic acid, was added dropwise a solution of 2.6 g. of bromine in 26 cc. of acetic acid. The solution was concentrated under reduced pressure and diluted with water. The separating solid was recrystallized from methanol to give 2.5 g. of the lactone of rac. α -(3-keto-4,9-dimethyl-5-
 15 hydroxy-1,2,3,5,6,7,8,9-octahydro-6-naphthyl)-propionic acid D (VIII), M. P. 138° C.

A mixture of 2.5 g. of the lactone D (VIII) in 50 cc. of ether and 1.6 g. of bromine in 16 cc. of acetic acid was refluxed for 40 minutes on a water bath. After
 20 evaporating the ether, the residual solution was diluted to afford 1.0 g. of the lactone of rac. α -(3-keto-4,9-di-
 25 methyl-2-bromo-5-hydroxy-1,2,3,5,6,7,8,9-octahydro-6-
 naphthyl)-propionic acid D (VII) which was dehydro-
 brominated to rac.-santonin D (IX) in the same way as
 described in Example 1.

What is claimed is:

1. A method for the manufacture of a racemic santonin having a melting point of 190° C. (uncorr.), which comprises subjecting the lactone of racemic α -(3-keto-4,9-di-
 30 methyl-2-halogeno-5-hydroxy-1,2,3,5,6,7,8,9-octahydro-6-
 naphthyl)-propionic acid to the action of a dehydrohalogenating agent selected from the group consisting of bases of the pyridine series and metal halides, whereby the 2-
 35 positioned halogen is split off and a double bond is formed between C_1 and C_2 .
2. A method for the manufacture of a racemic santonin having a melting point of 190° C. (uncorr.), which comprises subjecting racemic α -(3-keto-4,9-dimethyl-1,2,3,5,6,7,8,9-octahydro-6-naphthyl)-propionic acid to the action
 40 of two equivalents of free halogen whereby the halogen is introduced at each of the 2- and 5-positions, and subjecting the product to the action of a dehydrohalogenating agent selected from the group consisting of bases of the pyridine series and metal halides whereby the halogen at
 45 C_5 and the hydrogen of the carboxyl radical at C_{11} split off as hydrogen halide forming a lactone ring, and the halogen is split off at C_2 forming a double bond between C_1 and C_2 .
3. A method for the manufacture of a racemic santonin
 50 having a melting point of 190° C. (uncorr.), which comprises subjecting racemic α -(3-keto-4,9-dimethyl-1,2,3,5,6,7,8,9-octahydro-6-naphthyl)-propionic acid to the action of one equivalent of free halogen whereby the halogen is introduced at the 5-position, subjecting the product to
 55 the action of a dehydrohalogenating agent selected from the group consisting of bases of the pyridine series and metal halides whereby the halogen at C_5 and the hydrogen of the carboxyl radical at C_{11} split off as hydrogen halide forming a lactone ring, subjecting the product to
 60 the action of one equivalent of free halogen whereby the halogen is introduced at C_2 , and subjecting the product to the action of a dehydrohalogenating agent selected from the group consisting of bases of the pyridine series and metal halides whereby the halogen at C_2 is split off
 65 and a double bond is formed between C_1 and C_2 .

4. A process according to claim 1, wherein the dehydro-
 halogenating agent is γ -collidine.

5. A process according to claim 2, wherein the halogen is bromine and the dehydrohalogenating agent is γ -col-
 70 lidine.

6. A process according to claim 3, wherein the halogen is bromine and the dehydrohalogenating agent is γ -col-
 lidine.
